WIRES HANDLING APPARATUS

Phineas A. Beaman and John R. North, Worcester,
Mass., assignors to Morgan Construction Com-
pany, Worcester, Mass., a corporation of Massa-
chusetts

Application September 18, 1946, Serial No. 697,738

5 Claims. (CL 242—80)

1

This invention relates to wire handling apparatus, and more particularly to apparatus for handling bundles of drawn wire which is to be subjected to further drawing or other processing operations.

In the manufacture of steel wire in comparatively small sizes it is a common practice to produce an intermediate size of wire from rolled steel rod on a continuous multiple-block wire-drawing machine. Bundles of wire are removed from the finishing block of the machine and transferred to a second continuous multiple-block wire-drawing machine which serves to reduce the wire to the desired final size. Heretofore a stripper has been used to remove the wire bundles from the finishing block, and a separate device has been provided for supporting the bundles and paying off wire therefrom to the second wire-drawing machine. It has accordingly been necessary to transfer the wire bundles from the stripper to the bundle supporting device, and this operation has not only involved considerable labor but it has also frequently resulted in disarranged bundles from which the wire will not pay off properly.

It is accordingly one object of the invention to provide an improved apparatus for handling bundles of wire which is to be subjected to further operations, the apparatus being constructed and arranged to reduce the labor required and to avoid disarrangement of the bundles.

It is a further object of the invention to provide a novel device which will serve not only as a wire bundle stripper but also as a support for bundles as the wire is payed off therefrom.

It is a further object of the invention to provide an improved wire pay-off apparatus arranged to support a plurality of wire bundles from which the wire may be payed off successively to permit welding of the wire and drawing thereof in a continuous strand.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts,

Fig. 1 is a sectional elevation taken on the line

2

1—1 of Fig. 2 and showing a wire handling apparatus for paying off wire to a wire-drawing machine;

Fig. 2 is a plan view of the apparatus shown in Fig. 1;

Fig. 3 is an enlarged section taken on the line 3—3 of Fig. 1;

Fig. 4 is a section taken on the line 4—4 of Fig. 2;

Fig. 5 is a section taken on the line 5—5 of Fig. 2; and

Fig. 6 is an elevation showing a portion of the apparatus in position on the finishing block of a wire-drawing machine.

15 The invention provides a combined stripper and pay-off device 10 comprising four upright legs 11 connected at their upper ends to a central hub 12 by means of radial spokes 14. The legs 11 are also connected at points intermediate their lengths to a central vertical sleeve 15 by means of a horizontal web 16 which is cruciform in plan view, as shown in Fig. 2. At the lower end of each leg 11 there is provided an outwardly projecting foot 18. A separate hub 19 is attached to the top of the hub 12 by means of a vertical screw eye 20. Radial spokes 22 extend outwardly from the hub 19 to support a horizontal ring 23 concentric with the hub and located outwardly beyond the legs 11.

25 In Fig. 6 there is shown a portion of a wire-drawing machine 25 having a finishing block 26 which draws wire through a die 27. This block 26 is rotated about a vertical axis and in accordance with known practice it is provided with four circumferentially spaced vertical stripper slots or grooves 29. These slots 29 are arranged to receive the feet 18 and the lower portions of the legs 11 of the device 10. The block 26 also includes a vertical axially positioned pin 30 arranged to extend through the sleeve 15 and support the same laterally.

30 It will be apparent that with the device 10 in position on the block 26, a bundle 31 of wire may be formed on the block and around the upright legs 11. When this bundle has reached a sufficient size the machine will be stopped and the wire severed, whereupon a crane or hoist will be attached to the screw eye 20 and the device 10 will be lifted to strip the bundle from the block. Another device 10 may then be placed in the

block and another bundle started. In the meantime the first device 10 with the bundle thereon will be transferred to the apparatus shown particularly in Figs. 1 and 2.

This apparatus includes a horizontal circular plate or table 33 having a central upwardly extending hub 34 which is rotatably supported on a fixed vertical spindle 35. This spindle is mounted on a suitable foundation 37. Three equally spaced upright radial plates 38 connect the hub 34 with the table 33 and divide the space above the table into three compartments 39. Within each of these compartments there is provided an upright pin 41 with its lower end fixed to the table 33, each pin being arranged to enter the sleeve 16 of one of the devices 10 to support the same laterally. Four openings or pockets 42 are provided in the table 33, around each of the pins 41, in position to receive the feet 18 of the device 10. A U-shaped strap 43 extends across the bottom of each pocket. An L-shaped releasable latch 45 (Fig. 5) is pivotally mounted on a bracket 46 adjacent each of the pins 41 in position to engage the web 16 and hold the device 10 in place. A spring 47 urges the latch into engagement. Two clicker bars 49 (Fig. 4) are pivotally attached at their lower ends to the table 33 on opposite sides of each pin 41, these bars being arranged to rest laterally against the upper portions of the bundles 31 and aid in ensuring the orderly uncoiling thereof. The two bars 49 are equally spaced from the axis of the table in a symmetrical and compact arrangement.

The table 33 is located near a wire-drawing machine 51 having a first block 52 which draws wire through a die 53. Between this machine 51 and the table 33 there is provided an upright frame or column 55 having on its upper end a transverse beam 56 which projects over the table at a considerable distance above the same. A sheave 58 and an associated wire guide 59 are mounted on the projecting end of the beam 56, the guide 59 being directly above the path of the pins 41. A weighted carriage 61 is slidable vertically on the column 55 and on this carriage there is mounted a sheave 62 and an associated wire guide 63. A sheave 65 and an associated wire guide 66 are mounted on the other end of the beam 56. A sheave 68 and an associated wire guide 69 are mounted on a bracket 70 carried by the column 55, beneath the sheave 65. All four of the sheaves are located in a common vertical plane, and they are all rotatable about horizontal axes.

The operation of the invention will now be apparent from the above disclosure. Several of the devices 10 will be provided, and they will be placed successively on the finishing block 28 (Fig. 6) of the machine 25 to receive bundles of wire. As each bundle is completed, a suitable crane will be attached to the eye 28 and the loaded device 10 will be lifted from the block and transferred to one of the pins 41 of the table 33, where the upper end of the wire will be welded to the lower end of the wire in the preceding bundle. One of the loaded devices 10 will always be located in the pay-off position beneath the sheave 58, and the wire will travel upwardly from the upper end of the bundle around the outside of the ring 23, which will guide the wire in a circular path about the legs 11. After passing the ring 23, the wire will travel around the sheaves 58, 62, 65 and 68 in succession and thence through the die 53 to the block 52. As each con-

volution of wire is withdrawn from the bundle, the clicker bars 49 will lift slightly to allow the wire to pass from beneath them. This promotes orderly withdrawal of the wire and avoids kinks and snarls. The weighted carriage 61 will normally rest in its lowermost position, but will move upwardly in case a snarl forms and increases the wire tension, whereupon the machine 51 will be stopped either by the operator or automatically in known manner. Upon exhaustion of one bundle the operator will turn the table 33 one-third of a revolution to bring the next bundle into the pay-off position, so that the wire-drawing may proceed in a continuous manner. The latches 45 will hold the devices 10 firmly in place during the withdrawal of the wire, and yet they may be readily released manually to allow removal of empty devices. The pockets 42 serve to receive the feet 18 and to prevent the wire from becoming caught beneath these feet as the lowermost convolutions of the bundle are withdrawn.

Since each bundle 31 is supported on its corresponding device 10 not only during the formation of the bundle but also during its transfer to the table 33 and during its pay-off to the machine 51, the cost of handling the wire is greatly reduced and the possibility of entangling the convolutions of the bundles is minimized. Obviously, the wire-drawing machine 51 can be replaced by any machine for forming or otherwise operating upon the wire, without affecting the operation of the pay-off apparatus or requiring any modification in the structure thereof.

Having thus described our invention, what we claim as new and desire to secure by Letters Patent is:

1. Wire handling apparatus comprising a device including a plurality of upright legs connected to one another and having outwardly projecting feet on their lower ends, the device being adapted to be mounted on the finishing block of a wire-drawing machine to receive a bundle of wire and to strip the bundle upwardly from the block, means at the upper end of the device to guide wire in a circular path about the legs as the wire is withdrawn upwardly from the upper portion of the bundle, a horizontal substantially circular plate mounted for rotation about a vertical axis and constructed to support the device at any one of a plurality of stations spaced about the axis of the plate, whereby the loaded device may be placed upon the plate at one of said stations and subsequently moved to a predetermined pay-off position by turning the plate, and wire withdrawing means at one side of the plate and including wire guide means projecting over the loaded device when the latter is in the pay-off position to guide the wire traveling upwardly from the device.

2. Wire handling apparatus, as set forth in claim 1, in which the plate is provided on its upper surface with a central upwardly extending hub and with upright substantially radial plates located between the stations and connecting the plate to the hub.

3. Wire handling apparatus as set forth in claim 1, in which the plate is provided at each station with a clicker bar pivotally secured at its lower end to the plate and arranged to rest laterally against the bundle to prevent snarling of the wire.

4. Wire handling apparatus as set forth in claim 1, in which the plate is provided at each station with two clicker bars pivotally secured at their lower ends to the plate and arranged to

rest laterally against diametrically opposite sides of the bundle to prevent snarling of the wire, the said two clicker bars being equally spaced from the axis of the table in a symmetrical arrangement.

5. Wire handling apparatus as set forth in claim 1, in which an upright pin is fixed to the plate at each station, and the device includes a central sleeve arranged to fit over the corresponding pin.
